UNITED STATES PATENT OFFICE

EDGAR EGAN, OF MEADOW GROVE, NEBRASKA

INCUBATOR

Application filed August 10, 1928. Serial No. 298,805.

This invention relates to an improved type of incubator embodying among other characteristics a heating apparatus adapted to keep the atmosphere at a constant temperature.

Another object of the invention contemplates a deflecting apparatus by means of which the heat may be evenly distributed within the bottom of the incubator.

10 An additional object of the invention comprehends fan members preferably located within the top of the incubator to facilitate circulation of the atmosphere.

A cardinal object of the invention resides 15 in the provision of racks and frames therefor to sustain eggs and by which the same may be tilted.

More specifically stated the racks are adapted for shifting movement to tilt the 20 frames therefor.

With the above and other objects in view, the invention further consists in the following novel features and details of construction, to be hereinafter more fully described, illustrated in the accompanying drawings and 25 pointed out in the appended claims.

In the drawings:

Figure 1 is a vertical sectional view taken 30 through the completed invention.

Figure 2 is a sectional view taken on line 2-2 of Figure 1.

Figure 3 is a vertical sectional view taken 35 on line 3-3 of Figure 1.

Referring to the drawings in detail, where- 40 in like characters of reference denote corresponding parts, the reference character 10 indicates a pit sunk within the ground and having communication with a floor surface 11. An oil burner or other heating device,

such as indicated at 12, arranged within the 45 bottom of the pit is adapted for connection with a thermostat 13 through the instrumentality of a pipe line 14, the latter also being in communication with a fuel reservoir 15

which may be arranged for convenient re- 50 filling. An overflow pipe 15' is in communication with the oil burner whereby excess oil within the pit will be carried off instead of allowing the fumes therefrom to be circulated within the incubator.

Wall portions 16, supported upon the floor surface 11, are adapted to carry a roof, such as indicated at 17. A multiplicity of doors or other closures 18 are included within the side wall construction of the incubator.

Shoulder portions 19 within the pit 10 and disposed appreciable distances above the burner or heating element 12 are adapted to support receptacles 20 for water or other liquids which may be evaporated in conjunction with the heat, whereby the atmosphere will be humidified.

A deflector 21, carried by and elevated from the flooring 11 immediately above the pit 10, is adapted to collect and deflect or otherwise spread the heat from the pit across the flooring.

Fans 22, carried within the roof 17 and having communication with inlet ports 23, are adapted to keep the humidified atmosphere circulating within the incubator due to the specific shape of the upper surface of the deflector upon the side and end portions thereof. Discharge ports 24 located adjacent the ends and within the roof of the incubator 75 housing are adapted to provide the means to facilitate emission of foul air.

The air currents from the fans directed upon the inclined surfaces or facets of the deflector will cause the heated or humidified air 80 to be sucked or otherwise drawn outwardly from under the edges of the deflector and directed upwardly for contact with the eggs within the trays.

A vent pipe 25, extended from the heating element 12, is projected through both the deflecting dome 21 and roof 17, whereby the gases may be taken off from the heating element.

As a means for inducing the heating and circulation of air within the incubator, I provide a cold air inlet port 26 extended through the wall of the pit 10 and establishing communication at its ends with the interior of the incubator above the floor level and the bottom of the pit, whereby the mixing cold air with the heat emitted from the burner 12 and the humidity created in the evaporation of the liquid within the receptacle, by said heat, 100

will produce the desired atmosphere for the purposes of incubation.

Standards 28, supported upon the flooring 11 at the ends of the incubator and having connection at the uppermost ends with the undersides of the roof 17, are arranged in spaced parallel relation upon the opposite sides of an aisle within the housing. Access may be had to one end of the housing by one of the doors 18, inasmuch as the heat deflector 21 extends above the floor and is arranged in the path of movement through said aisle. For this purpose, other doors are provided within the sides of the housing to facilitate access to racks and trays therefor, the descriptions of which will presently follow.

Racks 29, preferably of angle bar construction and in the nature of elongated frames, substantially as illustrated in Figure 2 of the drawings, are tiltably mounted at intermediate points in their lengths upon rod members 30 having connection at their ends between adjacent standards 28.

Supporting bars 31 and 32 respectively, carried upon the outer sides of the end racks, are adapted for connection with rods 33 having connection with the undersides of each of the racks and remotely disposed with relation to the fulcrums 30. Trays 34 are carried by the racks and are preferably two in number within each. As illustrated in Figure 3 of the drawings, the lowermost ends of the supporting bars 31 and 32 are elevated from the floor surface 11 but when it is desired to tilt the racks 29 and trays 34 supported thereby, it is therefore necessary to remove bolt members 35 from locking arms 36 horizontally disposed adjacent the lowermost ends of the standards 28 and the supporting bars 31 and 32 will engage the upper surface of the flooring 11 as illustrated in dotted lines to the left in Figure 3 of the drawings.

The bolts 35 are also passed through the lowermost ends of the supporting bars 31. Removal of said bolts will permit tilting of the racks and trays to occupy either of the extreme positions, as illustrated by the dotted lines in Figure 3 of the drawings. Such movement is necessary at prescribed intervals to facilitate proper incubation of eggs. Such action will also cause the eggs to partially turn whereby other sides of the eggs may be heated.

The trays and frames, located adjacent the ends of the turning or tilting trays 34, are stationary. Said stationary frames are utilized for the supporting of chicks already hatched. The chicks after breaking through the shells upon the tilting trays 34 are then transferred to the trays upon the stationary frames; the latter having reticulated bottoms, whereby more air will circulate around the chicks to dry them off.

The invention is susceptible of various

changes in its form, proportions and minor details of construction, and the right is herein reserved to make such changes as properly fall within the scope of the appended claims.

Having thus described the invention, what is claimed is:—

1. In an incubator, a housing having a pit, a heating element arranged within the pit, moisteners for the air emitted from said pit, a deflector having inclined surfaces and extended over the pit and elevated from the bottom of the housing, egg trays arranged within the housing, and fan members directing air currents upon the inclined surfaces of the deflector to cause circulation of the generated air around and about said trays.

2. In an incubator, a housing having a pit, a heating element arranged within the pit, moisteners for the air emitted from the pit humidifying the quality thereof, a deflector arranged in spaced relation from the bottom of the housing over the pit having inclined upper surfaces, egg trays arranged within the housing upon opposite sides of the inclined surfaces of the deflector, and fan members arranged within the top of the housing above the trays for directing air currents upon the inclined surfaces of the deflector to create suction of the heated air beneath the deflector and circulate same around and about said trays.

3. In an incubator, a housing having a pit, a heating element arranged within the pit, moisteners for the air emitted from the pit humidifying the quality thereof, a deflector arranged in spaced relation from the bottom of the housing over the pit having inclined upper surfaces, egg trays arranged within the housing upon opposite side of the inclined surfaces of the deflector, fan members arranged within the top of the housing above the trays for directing air currents upon the inclined surfaces of the deflector to create suction of the heated air beneath the deflector and circulate same around and about said trays, and said trays being tiltably mounted.

In testimony whereof I affix my signature.

EDGAR EGAN.
